UNITED STATES PATENT OFFICE

161,815

HOLDER FOR PLAYING CARDS, OR SIMILAR ARTICLE

Wilber Francis Beeman, Chicago, Ill.

Application July 26, 1950, Serial No. 11,421

Term of patent 3½ years

(Cl. D34—13)

To all whom it may concern:

Be it known that I, Wilber Francis Beeman, a citizen of the United States and a resident of the city of Chicago, in the county of Cook and State of Illinois, have invented a new, original, and ornamental Design for a Holder for Playing Cards, or Similar Article, of which the following is a specification, reference being had to the accompanying drawing, forming a part thereof.

On the drawing:

Figure 1 is a perspective view of a holder for playing cards, or similar article, showing my new design; and

I claim:

The ornamental design for a holder for playing cards, or similar article, as shown.

WILBER FRANCIS BEEMAN.
